UNITED STATES PATENT OFFICE.

ALFRED DOUBLEDAY, OF CINCINNATI, OHIO.

COMBINED INK-FOUNTAIN AND PEN-HOLDER.

SPECIFICATION forming part of Letters Patent No. 251,705, dated January 3, 1882.

Application filed February 21, 1881. (No model.)

To all whom it may concern:

Be it known that I, ALFRED DOUBLEDAY, of Cincinnati, in the county of Hamilton and State of Ohio, have invented a new and useful Improvement in Removable Ink-Fountains for Pen-Holders, which improvement is fully set forth in the following specification and accompanying drawings, in which—

Figure 1 is a side view of a pen and pencil holder equipped with the removable ink-fountain. Fig. 2 is a side view of the ink-fountain removed from the holder. Fig. 3 is a perspective view of the ink fountain, and Figs. 4 and 5 are modifications.

The object of this invention is to provide a pen and pencil holder with a removable ink-fountain, and to adapt the ink fountain or cell to be readily secured to an object preparatory to use.

To this end I provide the end of the holder A opposite to the pen with a fountain, B. This fountain may be of any convenient length and adapted to slide entirely within the holder, or only a portion of it placed in the holder, and the other part constructed of the same diameter as the holder or staff. The upper end of this fountain is provided with a thread internally and a rubber head, C, screwed therein. This head C answers the purpose of an eraser, as in the ordinary pencil. The lower end of this fountain is permanently closed, and a stylus or pin, D, projects therefrom.

When desired for use the fountain or cell B

is drawn from the pen-staff and the pin D forced down into the table or other convenient resting-place, as shown in Fig. 3. The fountain thus remains erect, and the cork or head C can be removed, enabling the writer to use the ink from the fountain.

It will be observed that this invention requires the pen-holder to be tubular and is designed for that class of holders; but in case it is desired to attach the fountain to wooden holders, or to those not made of metallic substances, the upper end of the holder must be made tubular to receive the lower end of the fountain.

Having described my invention, what I claim as new, and desire to secure by Letters Patent, is—

1. A removable ink-fountain in pen-holders, having a pin projecting from its lower end, as herein specified.

2. A removable ink-fountain for pen-holders, provided at its lower end with a projecting pin and having its upper end closed with a rubber cork or head, as herein set forth.

3. A tubular pen holder or staff, in combination with a removable ink cell or fountain having a pin projecting from its lower end and its upper end closed with a rubber cork or head, as and for the purpose herein set forth.

ALFRED DOUBLEDAY.
